UNITED STATES PATENT OFFICE.

FRANK MOSSBERG, OF ATTLEBORO, MASSACHUSETTS, ASSIGNOR TO MOSSBERG
PRESSED STEEL CORPORATION, OF ATTLEBORO, MASSACHUSETTS, A CORPO-
RATION OF MASSACHUSETTS.

REEL OR BEAM.

1,341,817.

Specification of Letters Patent.

Patented June 1, 1920.

Application filed September 15, 1919. Serial No. 323,864.

To all whom it may concern:

Be it known that I, FRANK MOSSBERG, a citizen of the United States, and resident of Attleboro, in the county of Bristol and State of Massachusetts, have invented certain new and useful Improvements in Reels or Beams, of which the following is a specification.

This invention relates to reels or beams of the character on which yarn, wire or the like is wound; and the object of this invention is to provide such a reel or beam which is strong and durable and inexpensive in construction, the same being provided with rib recesses formed in the inner face of each of its head members, and means being provided for closing said recesses for a portion of their length at and adjacent to the juncture of the body portion and the heads for the purpose of preventing the yarn or material wound upon the reel from becoming crowded or jammed into said recesses and also providing simple and effective means for centrally supporting the body portion on the heads.

With these and other objects in view, the invention consists of certain novel features of construction, as will be more fully described, and particularly pointed out in the appended claims.

In the accompanying drawings:

Figure 1— is an end view of the head member.

Fig. 2— is a sectional elevation on line 2—2 of Fig. 1.

Fig. 3— is a section on line 3—3 of Fig. 1, showing the recessed closing member located in the recess formed in the head-plate.

Fig. 4— is a perspective view showing a detail of the rib recess closing member and body-centralizing member.

Fig. 5— is a section through the body portion on line 5—5 of Fig. 2.

Referring to the drawings, 10 designates the two head members which are secured to opposite ends of the body portion 11. Each of these beam-heads is provided with a main plate 12 whose center portion 13 is pressed outwardly from the plane thereof and which plate is also recessed at intervals as at 14 providing radial, stiffening ribs 15.

In some instances it is found necessary that these rib recesses should be closed at the line of juncture between the body and head-plates, and it is also of advantage that

these closing members extend outwardly 55 from the juncture line so as to effectually prevent the yarn from being crowded or forced into these rib recesses to prevent binding or jamming that portion which is called upon to withstand the greatest crowding pressure.

To accomplish this closing of the recesses in a simple and effective way, I have provided a plurality of members 16 which are shaped to set into the rib recesses 14 so that 65 the outer face of each will be flush with the plane of the inner face of the head. The inner ends of each of these members is preferably turned inwardly as at 17 forming a plurality of centralizing, supporting shoulders over which the ends 18 of the tubular body portion fit and these members are provided with an elongated portion adapted to fit into and close the rib recesses for a distance outward beyond the juncture line of 75 the body and the head members. These members 16 may be secured in these rib recesses by any suitable means but I preferably secure them by spot-welding.

The outer ends 19 of these members are 80 preferably turned inwardly into these rib recesses so as to effectually prevent any possibility of the yarn wound upon the body, to catch on these ends.

The opposite head members of this beam 85 or reel may be connected to the body portion by any suitable means but I have shown a central tubular member 20 having its ends 21 riveted into the opposite head members, and I have also shown a series of through 90 bolts 22 for further assisting in binding the head to the ends of the body members.

A reel of my present construction is very simple and inexpensive to make and is practical and effective in its operation.

The foregoing description is directed solely toward the construction illustrated, but I desire it to be understood that I reserve the privilege of resorting to all the mechanical changes to which the device is 100 susceptible, the invention being defined and limited only by the terms of the appended claims.

I claim:

1. A reel or beam comprising a body having a head secured at either end thereof, each of said heads having a main plate recessed at intervals on its inner surface form-

ing hollow, stiffening ribs, and a set of independent, elongated members secured in said rib recess closing the same at and for a distance outside the line of juncture of said body and head.

2. A reel or beam comprising a body having a head secured at either end thereof, each of said heads having a main plate recessed at intervals on its inner surface forming hollow, stiffening ribs, a set of members secured in said rib recess closing the same at and for a distance outside the line of juncture of said body and head, said members having portions extending into the ends 10 of said body portion to centralize the same.

3. A reel or beam comprising a body having a head secured at either end thereof, each of said heads having a main plate recessed at intervals on its inner surface forming hollow, stiffening ribs, and a set of L-shaped fingers secured in and closing said rib recesses at and for a distance outside the line of juncture of said heads and body, the outer ends of fingers being turned inwardly into said recesses and the inner ends 20 25 of said fingers engaging the ends of said body to centrally support the same.

In testimony whereof I affix my signature.

FRANK MOSSBERG.
